DESIGN FOR A SIGNAL CASING

Carl A. Glock, Lynwood, Calif., assignor to Pacific Signal Company, Lynwood, Calif., a corporation of California

Application March 13, 1934, Serial No. 51,036

Term of patent 7 years

To all whom it may concern:

Be it known that I, CARL A. GLOCK, a citizen of the United States, residing at Lynwood, in the county of Los Angeles and State of California, have invented a new, original and ornamental Design for a Signal Casing, of which the following is a specification, reference being made to the accompanying drawing forming a part thereof:

Figure 1 is a front elevational view of a signal casing showing my new design;

Figure 2 is a rear elevational view of a signal casing showing my new design; and

Figure 3 is a side elevational view of a signal casing showing my new design.

I claim:

The ornamental design for a signal casing, as shown.

CARL A. GLOCK.
